UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

NEEDLE-OPERATING MECHANISM FOR SEWING-MACHINES.

1,252,015.

Specification of Letters Patent.

Patented Jan. 1, 1918.

Application filed January 7, 1915. Serial No. 938.

To all whom it may concern:

Be it known that I, JAMES R. MOFFATT, a citizen of the United States, residing at Chicago, in the county of Cook, State of Illinois, have invented certain new and useful Improvements in Needle-Operating Mechanism for Sewing-Machines, of which the following is a description, reference being had to the accompanying drawing and 10 to the figures of reference marked thereon.

The invention relates to new and useful improvements in needle operating mechanism for sewing machines and more particularly to the mounting of the needle lever 15 which reciprocates the needle bar.

An object of the invention is to provide a needle lever and supporting means therefor, which is so constructed that the needle lever may be adjusted in a direction transversely of the plane of its oscillation for bringing said needle lever into proper alignment with the needle bar.

A further object of the invention is to provide a needle lever supporting means of 25 the above character, wherein the needle lever is so connected to its oscillating supporting sleeve that said needle lever may be shifted endwise of the sleeve for proper positioning the needle relative to the needle 30 bar.

These and other objects will in part be obvious and will in part be hereinafter more fully described.

In the drawings which show by way of 35 illustration one embodiment of the invention—

Figure 1 is a front view of a sewing machine embodying my improvements;

Fig. 2 is a plan view thereof;

Fig. 3 is a horizontal sectional view 40 through a portion of the overhanging arm, the needle lever and the supporting means therefor;

Fig. 4 is a section on the line 4—4 of

Fig. 3;

Fig. 5 is a view similar to Fig. 3, showing a modified form of supporting means for the needle lever;

Fig. 6 is a sectional view on the line 6—6

of Fig. 5;

Fig. 7 is a view similar to Fig. 3, showing a further modified form of the supporting means for the needle lever; and

Fig. 8 is a perspective view showing the

bushing detached and the pivot stud of the 55 construction shown in Fig. 7.

The invention consists generally in providing a needle lever which is oscillated about a supporting pivot for reciprocating the needle bar. This needle lever is pivotally supported on the overhanging arm of the machine and in one form of the invention the lever is attached to the support therefor, so that it may be shifted endwise 60 of the support or in a direction transversely of the plane of oscillation of the needle bar. The needle lever is preferably located in a plane containing the needle bar. In order that this needle lever may be properly positioned for connection to the needle bar in 65 the assembling of the parts, it is extremely desirable to have some means which will permit the lateral shifting of the needle lever so as to bring it into proper alignment with the needle bar. This shifting of the 70 needle lever on its supporting sleeve 75 accomplishes this result.

In another form of the invention the pivot stud which carries the needle lever is mounted in a bushing which may be adjusted endwise for accomplishing this purpose.

Referring more in detail to the drawings, I have shown my invention as applied to a sewing machine having a supporting bed 1, a work support 2, a standard 3, which carries an overhanging arm 4. The overhanging arm 4 carries bearing blocks 5 and 6, in which reciprocates a needle bar 7. The needle bar 7, as herein shown, carries the needles 8 and 9. The needle bar is provided 85 with a collar 10 which has a laterally projecting ear 11. The needle bar is reciprocated by a needle lever 12 which is pivoted at 13 to the overhanging arm 4. This needle lever is connected by suitable spaced parallel links 14 to the projecting ear 11 on the 90 collar 10.

The needle lever 12 has an arm 15 which carries a ball stud 16. A link 17 engages the ball stud 16 and is rigidly attached to a 100 strap 18 coöperating with an eccentric on the main shaft 19 of the machine.

As shown in Figs. 1, 2 and 3 of the drawings, this needle lever is fixed to a sleeve 20 which is mounted so as to freely oscillate 105 on a supporting stud 21. The overhanging arm is formed with a socket 22 and with a threaded opening 23 which leads from the

socket to the rear face of the overhanging arm. The stud 21 is provided with a reduced threaded end 24 which engages the threaded opening 23 and a lock nut 25 holds the stud in place in the overhanging arm. The outer end of the stud 21 is provided with a head 26 and the sleeve 20 oscillates on the stud between the head 26 and the inner face of the socket 22. The sleeve 20 is formed with two spaced threaded sections 27 and 28 and with a smooth enlarged section 29 between the same. The needle lever is adapted to be placed on the sleeve and has an opening therethrough fitting the smooth section 29. A key 30, extends into a groove formed in the enlarged section 29 and a groove in the needle lever and prevents the needle lever from turning relative to the sleeve. A nut 31 engages the threaded section 27 and a nut 32 engages the threaded section 28. It will be readily seen that these nuts may be set up against the front and rear faces of the needle lever and will clamp the same firmly on the sleeve which oscillates on the supporting stud. By turning the nut 32 so as to move the same away from the lever and then turning up on the nut 31, the needle lever may be shifted relative to the sleeve on which it is mounted in a direction away from the overhanging arm. By turning the nuts in the opposite directions the lever may be shifted toward the overhanging arm. This permits the ready shifting of the needle lever so that its plane of oscillation may be brought into proper alinement with the line of reciprocation of the needle bar and thus a non-binding connection made between the needle lever and the ear on the collar carried by the needle bar.

In Figs. 5 and 6, I have shown a slightly modified form of the invention. In this form of the invention, the overhanging arm 4 is provided with a bushing 33. Located in the bushing 33 is an oscillating supporting stud 34 for the needle lever. This supporting stud is held in the bushing by a suitable nut 35 which bears against a washer 36. The other end of said stud is provided with a threaded section 37, a slightly reduced section 38 for the needle bar 12, and a further reduced section 39. A nut 40 engages the threaded section 37 and a nut 41 engages the threaded section 39. The smooth section 38 which carries the needle lever 12 is formed with a groove and a key 42 engages said groove and a groove in the needle lever and holds the needle lever from movement on the stud in a direction about the axis of the stud. By shifting the nuts 40 and 41 as described in connection with the nuts 31 and 32, the needle lever may be shifted in a direction endwise of its supporting stud or toward and from the overhanging arm.

In Figs. 7 and 8 of the drawings, I have shown a further modified form of the invention. In this form of the invention, the overhanging arm 4 is provided with a bushing 43, which is capable of endwise adjustment on the overhanging arm. Said bushing is threaded, as at 44, and a nut 45 engages said threads. The bushing is also threaded at 46 and a nut 47 engages these threads. The stud 48 is fixed to the needle lever 12 and oscillates in said bushing 43 and said stud is held in the bushing by a nut 49, which bears against a washer 50. The stud at the other end thereof is formed with a flange 51, an enlarged section 52 on which the needle bar is keyed and a nut 53 threaded on to the outer end of the stud clamps the needle bar from movement on the stud. By loosening the nut 45 the bushing 43 may be moved endwise in the overhanging arm and by turning up on the nut 47 it will be held in this adjusted position. This adjustment of the bushing 43 shifts the needle lever toward the overhanging arm. An adjustment of the nuts in the opposite direction will shift the needle lever away from the overhanging arm. By this shifting of the bushing the needle lever may be positioned so that its plane of oscillation will be in proper alinement with the line of reciprocation of the needle bar.

From the above description, it will be noted that in each form of the invention described, I have provided means whereby the needle lever may be shifted in a direction transversely of its plane of oscillation, so as to bring the needle lever in proper alinement with the needle bar.

It is obvious that minor changes in the details of construction and arrangement of parts may be made without departing from the spirit of the invention, as set forth in the pending claims.

Having thus described my invention, what I claim as new and desire to secure by Letters Patent, is:

1. In a sewing machine, the combination of an overhanging arm, a needle bar reciprocating in said arm, a needle carried thereby, a needle lever for reciprocating said needle bar, and means for pivotally supporting the needle lever, whereby the latter may be adjusted transversely of its plane of oscillation for alining the needle lever with the needle bar.

2. In a sewing machine, the combination of an overhanging arm, a needle bar reciprocating in said arm, a needle carried thereby, a needle lever for reciprocating said needle bar, and means for pivotally supporting the needle lever including threaded nuts, and devices whereby the adjustment of said threaded nuts will vary the position of the needle lever in a direction transversely of its plane of oscillation.

3. In a sewing machine, the combination of an overhanging arm, a needle bar reciprocating in said arm, a needle carried thereby, a needle lever for reciprocating said needle bar, and means for pivotally supporting the needle lever including a supporting stud, and means for shifting said needle lever in a direction endwise of said stud and holding said needle lever in an adjusted position. 10
4. In a sewing machine, the combination of an overhanging arm, a needle bar reciprocating in said arm, a needle carried thereby, a needle lever for reciprocating said needle bar, and means for pivotally supporting the needle lever including a supporting stud, an oscillating sleeve carried by said supporting stud, means for keying said needle lever to said sleeve, and means for shifting the position of the needle lever endwise of said sleeve and for holding said needle lever in an adjusted position. 15
5. In a sewing machine, the combination of an overhanging arm, a needle bar reciprocating in said arm, a needle carried thereby, a needle lever for reciprocating said needle bar, means for pivotally supporting said needle lever including a stud fixed to the overhanging arm, a sleeve oscillating on said stud, a needle lever keyed to said sleeve, whereby said sleeve oscillates with said needle lever, said sleeve having spaced threaded sections located on opposite sides of the needle lever, a threaded nut for each threaded section, said nuts being adapted to engage the opposite faces of the needle lever, whereby the adjustment of the nuts will vary the position of the needle lever on the sleeve. 20
